UNITED STATES PATENT OFFICE.

ALBERT ANTHONY RUPPERT, OF DETROIT, MICHIGAN, ASSIGNOR TO FISHER BODY CORPORATION, OF DETROIT, MICHIGAN, A CORPORATION OF NEW YORK.

AUTOMOBILE BODY CONSTRUCTION.

Application filed July 19, 1924. Serial No. 726,901.

This invention relates to arm rests for automobile bodies, especially closed bodies. It is the object of the present invention to provide removable arm rests for the rear seat of a closed body, which is built up of a wooden block, a cushion spring construction, and suitable upholstery or trimming, the whole being a unit construction which can be separately trimmed and removably attached to the arm rest board of the car.

In the drawings:

Fig. 1 is an inside elevation of a closed body, showing my improved arm rest in place.

Fig. 2 is a longitudinal section through the same.

Fig. 3 is a cross section through the same.

Fig. 4 is a section on the line 4—4 of Fig. 3.

Fig. 5 is a fragmentary plan view of the cushion frame.

The base or support is built up of the front upright *a*, the rear upright *b* and the cross block *c*, the latter secured to the former two by screws. The cross block is removably secured to the arm rest board *d* of the car by means of depending strips *f* which can be slipped into the clips *e*, secured to the arm rest board by means of screws. The lower ends of the uprights may be secured also to the arm rest board by means of screws (not shown) that pass through the screw holes *g*. The two uprights and the cross block form the removable support on which rests a spring cushion frame.

This is made up of a bottom frame, comprising the two channel strips *h* with their channels presenting toward each other. These are crimped over the coils of the inverted conical springs *i*. These conical springs give the necessary flare of the arm rest from top to bottom to give the desirable appearance, and also make the same comfortable. Along the top of the coil springs is a wire frame *j* clipped to the top coils and with the frame bars comparatively close together at the rear, but with one of the frame bars having an offset *k* to provide a wider spacing of the upper frame bars at the front. This gives the desired shape and contour to the arm rest which must taper off to almost nothing at the rear. This design is also carried out by the arrangement and design of the coil springs. The front five springs

are inverted conical springs to give the necessary flare and breadth at the front, while the rear two springs are cylindrical springs, much smaller. The conical springs are located at the wide spacing of the top frame bars while the cylindrical springs are located at the narrower spacing. This makes an arm rest construction which closely approximates in appearance the old type of arm rest construction made of a solid block of wood, and which was practically unyieldable except for the padding.

Preferably a canvas web *m* is drawn over the springs. There is then secured over the top of this webbing some heavy matted hair or wadding *n*, by means of a cover of canvas *o* which is stitched to the canvas webbing *m*. A high grade of curled hair *q* is then set over the webbing and the cover *o*, and then a cover of muslin *r* is drawn over the curled hair *q*. A layer of thin cotton wadding *s* is laid over this muslin, and then finally the plush trimming *t* is drawn over this. These various layers of cloth and wadding are tacked to the support as shown in Fig. 3 to provide a suitable trimming job. The exact character of the trimming is not so important.

What I claim is:

1. An arm rest for vehicle bodies, having in combination a wooden support comprising front and rear uprights with a cross block, the same all constructed of wood, means by which the support at its side may be secured to the arm rest board at the side thereof, a cushion spring construction mounted on the top of the support and trimming drawn over the cushion spring construction and support.

2. An arm rest for vehicle bodies, having in combination a long and narrow support which may be secured along its long side to the side of the arm rest board of a vehicle body, a cushion spring construction supported on the top of the support and comprising a lower frame member and an upper frame member connected by a plurality of different sized coil springs, and trimming drawn over the upper frame member and the coil springs and the support.

3. An arm rest for vehicle bodies having in combination, a long and narrow support which may be secured along its long side to the sides of the arm rest board of a vehicle body, cushion springs supported on the

support, some of which are invertedly conical to provide a flare from top to bottom, and trimming drawn over said springs and support.

- 5 4. An arm rest for vehicle bodies, having in combination a support securable to the side of an arm rest board, a spring construction secured to the top of the support and including a bottom frame and an upper frame having an offset to provide a relatively wide spacing at the front and narrow spacing at the rear, wide springs secured between the upper and lower frame at the front in connection with the wide spacing of the upper frame, and narrow springs secured at the rear between the upper and lower frame.

5. An arm rest for vehicle bodies, having in combination a support, coil springs mounted on the top of said support, a cushion element mounted on the top of said spring construction for forming a rest, trimming drawn over the said cushion element, spring construction and support, and means for securing the arm rest unit at its side to an arm rest board, said cushion element, and coil spring structure and support being of such size and so arranged for receiving the trimming that the general contour of the finished arm rest unit has a downward and rearward taper.

In testimony whereof I have affixed my signature.

ALBERT ANTHONY RUPPERT.
